UNITED STATES PATENT OFFICE

BRUNO HOFFMANN, OF SPANDAU-WEST, GERMANY, ASSIGNOR TO GENERAL ELECTRIC COMPANY, A CORPORATION OF NEW YORK

CENTRIFUGAL COMPRESSOR OR BLOWER

Application filed December 4, 1928, Serial No. 323,703, and in Germany December 8, 1927.

The present invention relates to centrifugal compressors or blowers and especially to centrifugal compressors and blowers wherein the impeller is overhung on one end of the shaft 5 with the suction side facing away from the bearing.

Centrifugal compressors or blowers having their rotors arranged overhung with the suction side of the impeller facing toward the bearing have the disadvantage that as a result of the adjacent end of the shaft bearing, the starting up is effected unfavorably. The disadvantage is overcome by arranging the overhung rotor so that the suction side of the impeller faces away from the bearing, but this arrangement has the disadvantage that a packing for the shaft must be arranged between the bearing and the impeller, a thing which tends to lengthen the overhung portion of the shaft. As a result, arrangements of this kind have been limited heretofore to compressors or blowers for relatively small pressures, for example pressures of the order of 0.1 to 0.2 atmospheres for in the case of higher pressures the packing or stuffing box becomes so long in order to pack efficiently against the higher pressure that the overhang of the rotor wheel reaches too great a value. Particularly is this true in the case of impellers operating at relatively high speeds on account of the high stresses which occur in the long overhanging part of the shaft.

The object of the present invention is to provide an improved construction and arrangement in a centrifugal compressor or blower of the type wherein the suction side faces away from the shaft whereby an effective packing for relatively high pressures (for example pressures of the order of .5 atmosphere or greater) is obtained, while at the same time the length of the overhanging portion of the shaft is kept comparatively short so that the stresses in the shaft are maintained at a permissible value.

For a consideration of what I believe to be novel and my invention, attention is directed to the following specification and the claims appended thereto.

In the drawing the figure is a sectional

view of a centrifugal compressor or blower embodying the invention.

Referring to the drawing, 1 indicates the casing of a centrifugal compressor or blower having a suction inlet 2 and a discharge passage 3. In the casing is an impeller 4 overhung on the end of a shaft 5. The casing and impeller structure illustrated are shown only by way of example and are to be taken as typical of any suitable construction. The 60 impeller sucks in the gas to be pumped, for example air, through the suction inlet 2 and discharges it through the discharge passage 3.

Connected to the left hand wall of casing 1, which is the high pressure side of the casing, is a housing 6 in which is a pedestal 7 on which a shaft bearing 8 is supported. Shaft 5 is mounted in the shaft bearing 8 and impeller 4 is overhung on the end of the shaft. 70

9 indicates a thrust bearing for shaft 5. 70

According to my invention, I utilize the bearing 8 as a part of the packing for the impeller shaft so that the packing proper may be made relatively short which in turn means that the length of the overhung portion of the shaft becomes relatively short.

To this end, I provide a relatively short packing 10 located between the impeller and the forward end of casing 6, such packing being directly adjacent the end of bearing 8, and between the packing and the bearing I provide an annular space 11 which is sealed from the remainder of the casing 6 by a suitable packing 12. As the packing 12 is arranged between non-rotating parts it can be 85 made tight easily. With this arrangement, it will be seen that leakage from the discharge side of the impeller to atmosphere must be through packing 10 and thence through the bearing 8 so that the bearing 90 serves as a part of the packing.

In the present instance the stationary portion of the packing is supported by an annular wall 13 which forms a part of the compressor casing, the packing 12 being arranged between the outer end of wall 13 and an adjacent surface of the shaft bearing 8. 95

The lower portion of bearing housing 6 forms an oil chamber 14 to which oil from 100

the bearing flows by way of passages 15 which connect with a central bearing chamber 16. Oil is supplied to the bearing from any suitable source of oil pressure and flows 5 from the bearing to chamber 14. The oil level in chamber 14 is maintained substantially constant by regulating the rate of withdrawal of oil therefrom, or in any other suitable way. Connected to chamber 11 is a 10 pipe 17 which projects down into the oil in chamber 14 and serves to carry leakage oil from the right hand end of the bearing to oil chamber 14. The packing 10 is made of a length such that pressure of the gas 15 leaking from it to space 11 is substantially the same as the pressure of the oil leaking from the bearing to space 11 whereby the one pressure substantially balances the other. The height of the oil in chamber 14 is main- 20 tained at a value such that the pressure in space 11 will not be sufficient under normal operating conditions to force gas through pipe 17. In other words, the oil in chamber 14 serves as a seal for pipe 17. Any leakage 25 of gas from space 11 must be by way of the bearing to chamber 16, whence it may escape to atmosphere or other region through passage 18 and pipe 19. The pressure of the oil flowing from the end of the bearing to 30 space 11 depends upon the bearing pressure and the rate of rotation of the shaft. If, due to abnormal operating conditions, the gas pressure in space 11 exceeds a predetermined high value the gas will blow out through 35 pipe 17, thus safeguarding the oil film in the bearing. Thus it will be seen that the pipe 17 serves normally as a seal to prevent gas escaping around the packing and serves also as a safety device to permit discharge 40 from space 11 in case the gas pressure therein becomes abnormally high.

With the above described arrangement it will be seen that in addition to providing a construction wherein the bearing serves as 45 a part of the packing for the rotor I provide at the same time a construction wherein the bearing and packing are supported by and arranged in the same housing. This arrangement is of advantage in that it gives 50 a compact construction and one which can be manufactured and installed at relatively low cost.

In accordance with the provisions of the patent statutes I have described the principle of operation of my invention, together with the apparatus which I consider to represent the best embodiment thereof, but I desire to have it understood that the apparatus shown and described is only illustrative and that the invention may be carried out by other means.

What I claim as new and desire to secure by Letters Patent of the United States, is:

1. Sealing means for a centrifugal com- 55 pressor or blower having a shaft and an im-

peller overhung on the end of the shaft with its suction side facing away from the shaft, comprising a bearing for the shaft, a casing for the impeller, a packing located between the shaft and said casing directly adjacent to said bearing, walls defining a sealed chamber between the adjacent ends of the bearing and packing, a pipe for conveying lubricant from said sealed chamber, and means providing a liquid seal for said pipe. 70

2. Sealing means for a centrifugal compressor or blower provided with a casing having a suction inlet on one side, a housing connected to its other side, a shaft, and an impeller overhung on the end of said shaft, comprising, a bearing in the housing for the shaft, a packing for the shaft, located directly adjacent to the end of said bearing and supported by said housing, walls defining a sealed chamber between the adjacent ends of the bearing and the packing, a pipe for conveying lubricant from said sealed chamber and means providing a liquid seal for said pipe. 80

3. Sealing means for a centrifugal compressor or blower provided with a casing having a suction inlet on one side, a housing connected to its other side, a shaft, and an impeller overhung on the end of the shaft, comprising, a bearing in the housing for the shaft, a packing for the shaft located adjacent to the end of said bearing, walls defining a sealed chamber between the adjacent ends of the bearing and the packing, a drain for said chamber and means forming a seal for said drain, said packing being so constructed and arranged that the pressure of the gas leaking from it is equal substantially to the pressure of the oil flowing from the bearing end. 90

In witness whereof, I have hereunto set my hand this 12th day of November, 1928.

BRUNO HOFFMANN.
